UNITED STATES PATENT OFFICE.

AUGUSTA E. KROENINGER, OF SAN ANTONIO, TEXAS.

SHOE-LACE FASTENER.

SPECIFICATION forming part of Letters Patent No. 660,643, dated October 30, 1900.

Application filed June 17, 1898. Serial No. 683,726. (No model.)

To all whom it may concern:

Be it known that I, AUGUSTA E. KROENINGER, a citizen of the United States, residing at San Antonio, in the county of Bexar and State of Texas, have invented a new and useful Shoe-Lace Fastener, of which the following is a specification.

Shoes of the type secured by means of laces are frequently a source of trouble and discomfort to the wearer by reason of the laces becoming untied and loosening the shoe, thereby requiring a relacing or retying, which cannot at all times be conveniently effected.

It is the object of the present invention to devise means for securing the end portions of the lace when tied into a bow-knot as well as the parts of the bow-knot, said means being in the shape of a clasp comprising companion plates pivotally connected and having a spring interposed between them with all the fastening portions below the pivotal connection, and the effect of the spring is thereby more strongly exerted, and being about the center a greater securing inclosure is provided below the pivotal connection, as well as portions of the plates above the said pivotal connection adapted for free movement toward each other in removing or pulling the fastening by opening the parts of the plates below the pivotal connection.

In order to secure the full benefits of the invention, the plates comprise a series or plurality of radial points having their terminal portion bent inwardly to form spurs or barbs to make positive engagement with the ends of the lace, and also supplied with the intermediate inwardly-extending barbs to grip into the bow-knot or loops of the same and prevent the latter from working loose. To prevent the loss of the clasp or disconnection thereof from the shoe, a clasp connection is provided and secured at one extremity to the shoe, and at the other is made fast to the clasp, and thereby the fastener is always in convenient or accessible position for instant use when desired.

In the drawings, Figure 1 is a perspective view of a portion of a shoe, showing the improved clasp applied thereto in operative position. Fig. 2 is a detail perspective view of the fastener. Fig. 3 is a top plan view of the fastener. Fig. 4 is a side elevation of the

fastener. Fig. 5 is a detail perspective view of one of the plates of the fastener looking toward the inner side of the same. Fig. 6 is a detail perspective view showing another form of flexible connection for the fastener.

Similar numerals of reference are employed to indicate corresponding parts in the several views.

The clasp or fastener is composed of companion plates of duplicate construction, each plate having a pair of ears 2 at directly-opposite points, which are adapted to coincide and are supplied with openings to receive a pivot-pin 3 by means of which the plates are movably connected, the said pin passing between the adjacent portions of the plate at the upper part thereof, and thereby leaving the greater portion of the plates below the pin free for performing the function of a fastener.

A coil-spring 4 is mounted on the pin 3, and its end portions are extended and engage with the upper inner portions of the said plates to force them apart and correspondingly press the lower end portions of said plates together in normal position to grip the shoe-lace placed between them with security and firmness. The plates 1 are formed with a plurality of radial points 5, which regularly taper and have their terminals bent inwardly to produce spurs or barbs 6, which penetrate the shoe-lace and make positive engagement therewith and prevent slipping of the fastener when in position. The points 5 are divergent and have considerable space between them, and by their divergence, together with the tendency to close instituted by the spring 4, the parts of the tied lace are held in proper relative position and prevented from working loose, and the fastener itself is also held in its applied position without liability of slipping. Additional spurs 9 are provided intermediate the points 5 and in the angle formed by adjacent spurs. Said additional spurs extend inwardly and are of such length as to provide an intermediate fastening to catch into the loops of the tied shoe-lace, and thus obviate the tendency of the said loops to work loose or pull and dispose the fastener in irregular position after a positive application.

The plates are struck up from sheet metal and are stiffened and strengthened by hav-

ing the points 5 pressed outwardly between their opposite converging side edges. By pressing the points 5 outwardly intermediate of their longitudinal edges inner extensions 5 are formed which engage with the shoe-lace and materially assist in preventing the accidental displacement of the fastening when in position. Moreover, by this construction the inner faces of the plates are provided with 10 recesses in their opposing sides, thereby enabling the knot to be received comfortably between the plates, whereas the outer end portions of the points will grip the loops and the loose ends of the lace and maintain all 15 the parts of the lace in proper relation.

In order to guard against the loss of the fastener or its displacement when the shoe is removed and laid aside, a flexible connection, 20 as a chain or cord 7, is applied to the fastener by means of a ring 10, provided at one end of the pivot-pin 3. The chain or cord 7 is adapted to be passed through the staple fastened to the top portion of a shoe and may at 25 times be slipped through an eyelet adjacently located or secured around one of the lacing-studs in accordance with the type of shoe on which the device is used, a pin or other suitable means of securing the cord to the shoe being also provided. This connection is very 30 effective in preventing accidental disengagement from the shoe, and the barbs 9 are ex-

ceptionally effective in the retention of the parts of the tied shoe-lace.

Having thus described the invention, what is claimed as new is—

A shoe-lace fastener comprising a pair of plates provided with inwardly-extending pivotally-connected ears near the upper extremities thereof and a coiled spring surrounding the pivotal device and operating to hold the 40 lower portions of the plates normally in contact, the ears, pivotal device and spring being confined completely between the upper extremities of the plates and the latter having below the center thereof widely-separated distinct converging points with inturned lower terminals bearing against each other and adapted to catch and hold the loose ends of the lace after the knot is tied, pairs of spurs extending inwardly from each plate in a plane 45 at right angles to the latter and located at the intersection of the edges of the points to provide holding means at an intermediate position to engage the knot which is inclosed by the plates.

In testimony that I claim the foregoing as my own I have hereto affixed my signature in the presence of two witnesses.

AUGUSTA E. KROENINGER.
